PORTABLE TAPE RECORDER

Leon S. Wirch, Rego Park, N.Y., assignor to Telectrosonic Corporation, Long Island City, N. Y., a corporation of New York

Filed June 28, 1962, Ser. No. 70,723

Term of patent 14 years

(Cl. D26—14)

Fig. 1.

Fig. 2.

Fig. 3.

Fig. 4

Fig. 5.

FIG. 1 is a perspective view of a portable tape recorder showing my new design with the cover in place;

FIG. 2 is a rear elevational view, to an enlarged scale;

FIG. 3 is a top plan view, to an enlarged scale;

FIG. 4 is a bottom plan view, to an enlarged scale;

FIG. 5 is a side elevational view, to an enlarged scale, the opposite side being substantially a mirror image thereof; and

FIG. 6 is a perspective view, to an enlarged scale, with the cover removed.

I claim:

The ornamental design for a portable tape recorder, as shown and described.
